C. W. KIRSCH & J. A. HENRY,
CURTAIN HOLDBACK FIXTURE,
APPLICATION FILED JAN. 8, 1915.

1,202,735.

Patented Oct. 24, 1916.

UNITED STATES PATENT OFFICE.

CHARLES W. KIRSCH AND JAMES A. HENRY, OF STURGIS, MICHIGAN, ASSIGNEES TO
KIRSCH MANUFACTURING CO., OF STURGIS, MICHIGAN, A CORPORATION OF
MICHIGAN.

CURTAIN HOLDBACK-FIXTURE.

1,202,735.

Specification of Letters Patent.

Patented Oct. 24, 1916.

Application filed January 8, 1915. Serial No. 1,238.

To all whom it may concern:

Be it known that we, CHARLES W. KIRSCH and JAMES A. HENRY, of Sturgis, St. Joseph county, Michigan, citizens of the United States, have invented certain new and useful Improvements in Curtain Holdback-Fixtures; and we do hereby declare the following to be a full, clear, and exact description of the invention, such as will enable others skilled in the art to which it appertains to make and use the same.

This invention relates to improvements in curtain hold-back fixtures adapted to be secured to window casings the object being to provide a device of this character which is capable of being adjusted to various positions to drape curtains to present more or less window opening therebetween and to be folded against the window casing when not in use.

The particular object of the invention is to provide a fixture of this character which is simple, cheap, easily secured in place and easily capable of adjustment or positioning as aforesaid.

The invention consists in the features of construction and combinations of parts hereinafter fully described and particularly claimed.

In the accompanying drawings illustrating the invention: Figure —1— is a view in front elevation of a hold-back fixture embodying our invention, a portion of the window casing to which it is secured being illustrated and the position of curtain held back therein indicated in dotted lines. Fig. —2— is a view similar to Fig. —1— showing the fixture in another position. Fig. —3— is a view similar to Fig. —1— showing the fixture folded flat against the window casing. Fig. —4— is a sectional view on the line 4—4 of Fig. —1—, a part of the fixture being broken away and the remainder shown in top plan view. Fig. —5— is a detail vertical section on the line 5—5 of Fig. —4—.

The said fixture comprises a bracket 1 consisting of an angle plate having one arm or flange secured to the window casing 2 and having its other arm or flange 3 horizontally disposed. Pivotedly secured to said arm 3 is an angle plate 4, the vertical arm of which carries the curtain hold-back loop 5, the latter being pivotally secured thereto at the

end of one of its arms. The said hold-back 55 loop is composed of a strip of an elastic sheet metal and is substantially U-shaped, one arm thereof being longer than the other and providing a curved extension 6 which projects inwardly toward the other arm, but 60 at a distance from the end of same substantially equal to the width of said member 5, the free end of said extension 6 being substantially in alinement with the shorter arm of said loop member. 65

The pivotal connections between the several parts mentioned are made by means of rivets or similar pivot pins 7, each of which passes through the parts pivotally secured together and through a washer 8, the end 70 portion projecting beyond said washer being turned over or flattened at its end to provide a bur or shoulder to prevent disengagement of the washer 8 therefrom. Between the head 9 of said rivet and the opposing flange or arm of the angle plate 4 we provide a spring washer 10, the latter being dished and provided with a plurality of radial arms which bear upon the face of the flange or arm of the angle plate 4 and 75 exert a pressure thereon thereby drawing the said flange of the angle plate 4 into close frictional contact with the part to which it is pivotally secured by said rivet, such as the horizontal arm 3 of the angle plate 1 or the 80 shorter arm of the loop member 5. 85

The loop member may be easily turned on either or both the pivotal axes mentioned to occupy a plurality of different positions. As shown in Fig. —1— said loop is disposed 90 at an incline and projects from the window casing in front of the window sash, (not shown), the lower end portion of the curtain being adapted to be passed through said loop member and held back substantially as 95 indicated in Fig. —1—. The elasticity of the metal of which the loop member 5 is composed permits the same to be opened so that the curtain may be inserted into said loop at a point between the free end of the 100 extension portion of the long arm thereof and the face of the window casing opposing the same. The shorter arm of said loop member is secured to that face of the vertical flange of the angle plate 4 which 105 opposes the window casing and when positioned as shown in Fig. —1— the lower edge of said shorter arm engages the upper edge

of the horizontal arm of said angle plate 4 which constitutes a stop for limiting the pivotal movement of said loop member in that direction.

5 In Fig. —2— the loop member is illustrated as extending in substantially the opposite direction from that indicated in Fig. —1— and when so disposed the curtain may be received in the space between the shorter 10 arm of said loop member and the opposed wall and portion of the window casing. If it is desired at any time to permit the curtain to hang down straight without being held back the angle plate 4 is swung so that 15 one side edge thereof is disposed parallel with the window casing and the loop member is vertically disposed and folded against the window casing as clearly shown in Fig.

3. The said loop member may be otherwise 20 positioned within the limits permitted by the several pivotal connections described. The said angle plate 1 may obviously be secured to a side edge of the window casing 2 as well as the front face of the same without materially affecting the positioning of 25 the loop member 5 with respect to the window. This is not illustrated in the drawings, being deemed superfluous.

The invention is simple and efficient and 30 affords a neat and ornamental curtain hold-back device which is more easily manipulated, and can be more satisfactorily adjusted than other curtain hold-back means heretofore generally employed.

35 We claim as our invention:

1. A curtain hold-back fixture comprising a bracket adapted to be secured to the window casing and having an outwardly extending substantially horizontal arm, an 40 angle plate having one arm pivotally secured to the arm of said bracket and adapted to swing in a horizontal plane thereon, and a curtain receiving loop pivotally mounted upon the vertical arm of said angle 45 plate to swing in a vertical plane thereon.

2. A curtain hold-back fixture comprising

a bracket adapted to be secured to the window casing and having an outwardly extending substantially horizontal arm, an angle-plate having one arm pivotally secured to the arm of said bracket and adapted to swing around in a horizontal plane, and a curtain receiving loop pivotally mounted upon the other arm of said angle-plate and adapted to swing up and down 55 thereon.

3. A curtain hold-back fixture comprising a loop member having a substantially fixed shape, and means secured thereto and interposed between the same and the window casing and adapted to be secured to the latter for permitting adjustment of said loop-member to a plurality of positions and in more than one plane.

4. A curtain hold-back fixture comprising a loop member having a substantially fixed shape, a supporting member carrying the same and adapted to be secured to the window casing, said loop member movable relatively to said carrying member on a 70 plurality of pivotal axes.

5. A curtain hold-back fixture comprising a loop member having a substantially fixed shape, an angle-plate having one of its arms pivotally secured to said loop-member an 75 angle bracket having one of its arms pivotally secured to the other arm of the angle-plate and adapted to be rigidly secured by its other arm to the window casing whereby said loop-member can be adjusted vertically and horizontally, and yielding elements interposed in said pivotal connections for resisting free relative movement of each of said parts with respect to the others.

In testimony whereof we have signed our 85 names in presence of two subscribing witnesses.

CHARLES W. KIRSCH.
JAMES A. HENRY.
